UNITED STATES PATENT OFFICE.

JOHN J. BROOKS, OF ATHENS, OHIO, ASSIGNOR OF ONE-HALF TO FRANK E. GOLDSBERRY, OF SAME PLACE.

DESIGN FOR A SAD-IRON.

SPECIFICATION forming part of Design No. 21,593, dated May 31, 1892.

Application filed April 4, 1892. Serial No. 427,750. Term of patent 3½ years.

To all whom it may concern:

Be it known that I, JOHN J. BROOKS, a citizen of the United States, residing at Athens, in the county of Athens and State of Ohio, have invented and produced a new and original Design for Sad-Irons, of which the following is a specification, reference being had to the accompanying drawings, forming a part thereof.

Figure 1 is a side elevation of a sad-iron, showing my design. Fig. 2 is a sectional view on line xx of Fig. 1; and Fig. 3 is a plan view, these views being deemed necessary to fully illustrate my design.

The characteristic or leading features of my design are the top plate d , provided with beveled sides, which converge to meet at the toe

and which, as shown at d^2 , are grooved to form scalloped upper edges in cross-section, and the top plate d , from which rises a handle-base e , the sides of which present the concaved bevel d^3 shown. From the handle-base e rises an approximately stirrup-shaped handle f , the base of said handle being flush with the upper side of the handle-base. 25

Having now fully described my invention, what I claim, and desire to secure by Letters Patent, is—

The design for a sad-iron, substantially as herein shown and described.

JOHN. J. BROOKS.

In presence of—

G. W. ULLVIN,
L. O. TULLIS.
